SNUBBER

Filed May 1, 1926

UNITED STATES PATENT OFFICE.

FLOYD A. HUFF, OF MANSFIELD, OHIO.

SNUBBER.

Application filed May 1, 1926. Serial No. 106,076.

This invention relates to snubbers and more particularly to a snubber or rebound check in which the checking operation is obtained by a cushioning fluid.

5 An important object of the invention is to provide in a device of this character a construction preventing the loss of the cushioning fluid due to the pressure produced in the snubbing action.

10 A further object of the invention is to provide a novel and improved valve construction for devices of this character whereby the movement of the body of the vehicle is unresisted by the snubber in one direction.

15 A further object of the invention is to provide a snubber structure which will check the rebound of the vehicle without offering any resistance to the movement of the springs of the vehicle in one direction.

20 These and other objects I attain by the construction shown in the accompanying drawings, wherein for the purpose of illustration is shown a preferred embodiment of my invention and wherein:

25 Figure 1 is a vertical sectional view through a snubber constructed in accordance with my invention;

30 Figure 2 is a second vertical sectional view at right angles to that shown in Figure 1 and taken on the line 2-2 of Figure 1;

35 Figure 3 is a detail view showing the arrangement of the relief groove.

40 Referring now more particularly to the drawings, the numeral 10 generally designates a drum-like casing having end walls 11 and 12 and a circular side wall 13 which is cast integrally with the end wall 11 and provides a means for attaching the end walls 12, as at 14. The inner face of the wall 11 is socketed, as at 15, for the reception of a shaft 16 and a bushing 17 for this shaft. The wall 12 has an opening 18 for the passage of the shaft 16 and surrounding this opening at the outer face of the wall 12 is an annular flange 19, the outer end of which is interiorly threaded, as at 20, to provide a mounting for a gland follower 21 compressing packing 22 about the shaft 16. The outer end of the shaft 16 is provided with means as a nut 23 whereby it may be rigidly affixed to a suitable support 24 which is preferably carried by the frame 25 of the vehicle. The support 24, in addition to providing means for attaching the

shaft to the vehicle frame, likewise provides means for attaching one end of a coil spring 26, as at 27. The opposite end of this coil spring is affixed to the drum by one of the 60 securing elements 14 and this spring tends to constantly rotate the drum in the direction of the arrow in Figure 1.

Adjacent their outer edges, the walls 12 and 11 have in opposed faces thereof sockets 28 receiving shoulders 29 formed upon opposite sides of a valve 30. A spring 31 engaging the casing 10 and the valve tends to constantly urge the valve in the direction of the arrow in Figure 1, forcing the 70 outer end 32 of the valve into engagement with the wall 13. This outer end forms a stop limiting the movement of the valve at a time when the valve is substantially radially disposed to the shaft 16. The valve 75 30 includes side flanges 33, the inner ends of which preferably engage against the shaft 16, as at 34, at the same time that the end 32 of the valve comes into engagement with the wall 13 to assist in holding the valve. 80 This valve has formed therein an opening 85 at present disclosed as provided by terminating the valve wall short of the inner ends of the flanges 33. The shaft 16 has a rigid piston 36, the outer end of which 90 slidably engages the wall 13 and the side faces of which fairly closely fit against the walls 11 and 12.

Upon the outer face of the wall 13 is secured one end of a flexible element 37, the 90 opposite end of which is attached to the axle 38 of the vehicle, this flexible element being passed about the perimeter of the drum in such manner that when the axle approaches the drum and the flexible element is slackened, the drum, in its rotation by the spring 26, will wind the flexible element upon the periphery of the drum. The securing means whereby the flexible element is attached to the drum preferably comprises a plate 39 having its inner face corrugated, as at 40, to securely clamp the flexible element to the periphery of the drum. This plate is maintained in position by a cap screw 41 which, when removed, provides access to the interior of the drum to permit introduction thereto of the cushioning fluid.

In the operation, when the drum is rotated in the direction of the arrow by the 110 spring 26, the cushioning fluid escapes past the valve 30 for the reason that the com-

pression which would otherwise be formed between the piston 36 and valve causes the valve to swing about its pivots against the action of the spring 31 to a position, as illustrated in dotted lines in Figure 1. It will be noted that the curved structure of the valve permits this valve to fairly closely conform to the wall of the drum so that ample space is provided for the passage of the cushioning fluid at this time. When the compression of the vehicle springs ceases and the rebound occurs, the piston moving in the opposite direction first reduces the pressure against the front face of the valve 30 so that the valve is permitted to close under the influence of its spring 31 and then forms a pressure at the rear face of this valve. The only escape for this pressure is through the opening 35 so that the speed of the rebound is controlled by the size of the opening 35.

It will be obvious that during the rebound, pressure is created between the piston 36 and the rear face of the valve 30 and that such pressure would tend to cause leakage about the shaft 16. In order to prevent such leakage and thus materially reduce the frequency at which the drum 10 must be refilled with the cushioning fluid, I form in the wall of the opening 22 and side wall 12 an annular groove 42 having a port 43 communicating with the interior of the drum 10 at a point just in advance of the front face of the valve 30. Since at any time there is pressure formed between the piston 36 and the rear face of the valve 33 there must be a corresponding tendency to vacuum between the opposite side of the piston 36 and the front face of the valve, it will follow that leakage about the shaft 16 to the groove will merely tend to provide a balanced condition within the groove in which there is no pressure.

As a convenient means for insuring against rotation of the shaft 16, the bracket engaging end of the shaft is provided at diametrically opposed points with flats 16^a, the perimeter of the shaft intermediate the flats being threaded, as at 16^b, for coaction with the nut 23. The opening 24^a of the bracket is shaped to closely fit the shaft at the flats, thus insuring against any possibility of rotation of the shaft so long as it remains engaged in the bracket.

Since the construction hereinbefore set forth is capable of a certain range of change and modification without materially departing from the spirit of the invention, I do not limit myself to such specific structure except as hereinafter claimed.

I claim:

1. In a snubber, a stationary shaft, a drum rotatable upon the shaft, the shaft having a piston substantially fitting the interior of the drum, a valve pivoted within the drum

and opening in response to pressure applied to one face thereof, said valve having an opening formed therein and with the exception of said opening sealing the space between the drum and said shaft against the passage of pressure when applied to the opposite face thereof, one wall of the drum affording a bearing through which the shaft extends and including means for packing the shaft, said wall of the drum having in its shaft confronting face a groove in communication with the interior of the drum between the piston of the shaft and the first named face of the valve when the valve is in the closed position.

2. In a device of the type described, a hollow drum, a stationary shaft upon which the drum is oscillatable and combining with the drum to produce in the interior thereof an annular fluid containing channel, a valve carried by the drum spring urged to a position where it substantially closes the channel and shiftable to a position where it lies closely against one wall of the channel and leaves the channel substantially uninterrupted, a piston rigidly mounted upon the shaft and substantially fitting between the walls of the channel, a spring urging rotation of the drum in one direction and a member connected with the drum to rotate it in the opposite direction.

3. In a device of the type described, a hollow drum, a stationary shaft upon which the drum is oscillatable and combining with the drum to produce in the interior thereof an annular fluid containing channel, a valve carried by the drum spring urged to a position where it substantially closes the channel and shiftable to a position where it lies closely against one wall of the channel and leaves the channel substantially uninterrupted, a piston rigidly mounted upon the shaft and substantially fitting between the walls of the channel, a spring urging rotation of the drum in one direction and a member connected with the drum to rotate it in the opposite direction, said drum when rotated under the influence of said spring applying the pressure generated between the piston and the valve in a direction to open the valve.

4. In a device of the type described, a hollow drum, a stationary shaft upon which the drum is oscillatable and combining with the drum to produce in the interior thereof an annular fluid containing channel, a valve carried by the drum spring urged to a position where it substantially closes the channel and shiftable to a position where it lies closely against one wall of the channel and leaves the channel substantially uninterrupted, a piston rigidly mounted upon the shaft and substantially fitting between the walls of the channel, a spring urging rotation of the drum in one direction and a member

connected with the drum to rotate it in the opposite direction, one wall of the casing having an opening through which the shaft passes and in which the shaft is rotatably mounted, the shaft confronting face of the wall having a groove, the groove opening through the wall of the channel at that side of the valve which approaches the piston as the drum is rotated under the influence 10 of said spring.

5. In a device of the type described, a hollow drum, a stationary shaft upon which the drum is oscillatable and combining with the drum to produce in the interior thereof an annular fluid containing channel, a valve carried by the drum spring urged to a position where it substantially closes the channel and shiftable to a position where it lies closely against one wall of the channel and 15 leaves the channel substantially uninterrupted, a piston rigidly mounted upon the shaft and substantially fitting between the walls of the channel, a spring urging rotation of the drum in one direction and a member connected with the drum to rotate it 20 in the opposite direction, said valve when in the first named position having a wall thereof squarely abutting a wall of the channel to limit its movement.

6. In a device of the type described, a hollow drum, a stationary shaft upon which the drum is oscillatable and combining with the drum to produce in the interior thereof an annular fluid containing channel, a valve carried by the drum spring urged to a position where it substantially closes the channel and shiftable to a position where it lies closely against one wall of the channel and leaves the channel substantially uninterrupted, a piston rigidly mounted upon the shaft and substantially fitting between the walls of the channel, a spring urging rotation of the drum in one direction and a member connected with the drum to rotate it in the opposite direction, 25 30 35 40 45

the valve being pivoted upon a pivot paralleling the shaft and having guiding flanges slidably engaging the side walls of the channels, the terminal portions of said flanges when the valve is in the first named position engaging against the shaft. 50

7. In a snubber, a bracket adapted for attachment to a portion of a vehicle, a shaft having flats adjacent one end thereof, the perimeter of the shaft at said end being 55 threaded, the bracket having an opening shaped to fit the flatted end of the shaft and a nut engaging the threads of the shaft for securing it in position in the opening of the bracket, a drum rotatable upon the shaft, the shaft having a piston substantially fitting the interior of the drum, a valve pivoted within the drum and opening in response to pressure applied to one face thereof, said valve having an opening 60 formed therein and with the exception of said opening sealing the space between the drum and said shaft against the passage of pressure when applied to the opposite face thereof. 65

8. In a snubber, a stationary shaft, a drum rotatable upon the shaft, the shaft having a piston substantially fitting the interior of the drum, a valve pivoted within the drum and opening in response to pressure applied to one face thereof, said valve having an opening formed therein and with the exception of said opening sealing the space between the drum and said shaft against the passage of pressure when applied to the opposite face thereof, the perimeter of the drum having an opening permitting the insertion of fluid, a flexible element extending partially around the periphery of the drum and means for securing one end of the flexible element to the drum including a part sealing said opening. 70 75 80 85

In testimony whereof I hereunto affix my signature.
